James Desamuelton

UNITED STATES PATENT OFFICE.

GEORGE HUEBNER, OF LAGRANGE, TEXAS.

TENT-FRAME.

974,491.

Specification of Letters Patent. Patented Nov. 1, 1910.

Application filed June 20, 1910. Serial No. 567,872.

To all whom it may concern:

Be it known that I, GEORGE HUEBNER, a citizen of the United States, residing at La-
5 grange, in the county of Fayette and State of
Texas, have invented certain new and useful
Improvements in Tent-Frames, of which the
following is a specification, reference being
had to the accompanying drawings.

This invention relates to improvements in
10 tent-frames; and an object of this invention
is to provide a tent-frame which will be
simple in construction, relatively cheap in
manufacture and most efficient in use.

Another object of this invention is to pro-
15 vide a tent-frame which may be readily as-
sembled and placed in position, especially
under adverse conditions, as in the darkness
of the night when a light is not available.

In the drawings illustrating the principle
20 of this invention and the best mode now
known to me of applying that principle,
Figure 1 is a perspective view of my new
tent-frame assembled; Fig. 2 is a perspective
25 view showing my new tent-frame covered
with canvas; Fig. 3 is a detail in elevation
showing the tentpole supporting devices;
Fig. 4 is a detail in plan of the tentpole sup-
porting members; Fig. 5 is a section on the
30 line A—A of Fig. 4, one of the tentpoles be-
ing shown in place; and Fig. 6 is a detail in
perspective showing the manner in which
the canvas is attached to the tentpoles near
the bottom thereof.

My new tent-frame consists essentially of
35 tentpole supporting members and the tent-
poles which are supported thereby.

The tentpole supporting members consist
of a pair of strap-members or leaves *a* which
are connected by the hinge-pin *b* to form
40 what is commonly called a strap-hinge. On
each of the strap-members *a* of the strap-
hinge is pivotally mounted a pair of collars
c which are tapering in form and which turn
45 on the pivot-pins *d*. Into each of these col-
lars *c* is inserted the shouldered upper end
of a tentpole *e*. These tentpoles may be
made of any material, such as wood, iron
50 pipe or the like and will be fastened by
means adapted to the particular material
used. In the drawings the material shown
as used is wood and the fastening device is a
simple screw *f* passed through the screw
hole *g* (Fig. 5).

To one of the straps *a* is fastened a plate *h*

the ends *i* of which are curved toward each 55
other to form stop-lugs which limit the dis-
tance that the tentpoles between these lugs
may be spread (Fig. 3).

In each of the tentpoles is inserted a screw
eye *j* to which is attached one corner of the 60
hammock *k*.

Near the bottom of each tentpole is in-
serted a screw eye *k'* having an elongated
eye *k''* through which is passed one end of a
leather strap *m* the other end of which is 65
provided with a buckle. The strap *m* is
sewed to the tent canvas *n*, and by the
simple fastening device illustrated in Fig.
6, the tent canvas is prevented from slipping
upward on the tent frame. 70

To set up the tent, the tent-frame is as-
sembled by placing the upper ends of the
tentpoles in the collars *c*, these poles being
held together. The front legs are spread
apart and then the rear legs are pushed back 75
and spread apart to their proper place. The
front legs are next finally positioned by be-
ing spread apart as far as the stop-lug *i*
will permit. The canvas *n* is then placed
over the tent-frame. It is obvious that only 80
a very short time is necessary to erect the
tent the number of operations being small
and the character of these operations being
simple. My new tent frame is as readily
85 dismantled as it is assembled.

I claim:

1. A tent-frame consisting of a hinge hav-
ing a pair of leaves; a pair of tubular col-
lars pivotally mounted on each of said leaves;
and tent-poles having their upper ends 90
snugly fitted in and readily removable from
said collars.

2. A tent-frame consisting of a hinge hav-
ing a pair of leaves; a pair of tubular col-
lars pivotally mounted on each of said leaves; 95
tent-poles having their upper ends snugly
fitted in and readily removable from said
collars; and lugs which project from the
ends of one of said leaves to limit the swing
of a pair of said tent-poles. 100

In testimony whereof I hereunto set my
hand at Lagrange, Texas, this the thirtieth
day of April, 1910, in the presence of the
two undersigned witnesses.

GEO. HUEBNER.
